UNITED STATES PATENT OFFICE.

MARTIN W. BRUESHABER, OF CHICAGO, ILLINOIS, ASSIGNOR TO GOSS PRINTING PRESS COMPANY, A CORPORATION OF ILLINOIS.

PRINTING PRESS.

Application filed July 2, 1923. Serial No. 648,957.

The invention relates to printing presses, and more especially to novel and useful improvements in printing press inking mechanisms.

5 Objects and advantages of the invention will be set forth in part hereinafter and in part will be obvious herefrom, or may be learned by practice with the invention, the same being realized and attained by means 10 of the instrumentalities and combinations pointed out in the appended claims.

The invention consists in the novel parts, constructions, arrangements, combinations and improvements herein shown and described.

15 The accompanying drawings, referred to herein and constituting a part hereof, illustrate one embodiment of the invention, and together with the description, serve to explain 20 the principles of the invention.

Of the drawings:

Fig. 1 is a fragmentary, side elevation of the inking mechanism of a printing press;

Fig. 2 is an enlarged fragmentary detail 25 of the position regulating means applied to the form inking rollers;

Fig. 3 is a fragmentary section taken substantially on the line 3-3 of Fig. 2;

Fig. 4 is a fragmentary enlarged elevation 30 of another form of position regulating means applied to the inking rolls;

Fig. 5 is a fragmentary horizontal section taken substantially on the line 5-5 of Fig. 4; and

35 Fig. 6 is a diagrammatic view corresponding to Fig. 1.

The invention is principally and primarily directed to more efficient and uniform inking action, especially in connection with 40 high speed rotary printing. In certain of its features, it is directed more especially to effecting these results in connection with form cylinders of printing couples adapted to be rotated in both directions, depending 45 upon the nature or kind of product desired.

The objects and advantages are attained 50 by my invention through the relative position, sizes or proportions, and other characteristics of the ink drums, ink rollers, and other members of the inking system with 55 respect to each other, with respect to the form cylinder, and also to its two directions of rotation. Cooperating with the foregoing are means for nicely and accurately positioning the form rollers and other inking

rollers relatively to the impression cylinders, the inking drums and other devices and mechanisms.

Other features of the invention will be set forth primarily in connection with the following detailed description of the present preferred embodiment; and it will be understood that the preceding general description and the following detailed description are exemplary and explanatory but not restrictive of the invention.

Referring now to the embodiment of the invention by way of example illustrated in the accompanying drawings, a general frame 1 of a printing press is shown, and an inking fountain 2 of any suitable or convenient form is mounted thereon and is provided with a fountain roller 3, which likewise may be of any known or convenient form, and may be either continuously or intermittently rotated. Any suitable device 4 for regulating the ink supply from the fountain to the roller 3 may also be provided.

A ductor roller 5 reciprocates or oscillates intermittently between the fountain roller 3 and an ink drum 6, which may be styled the receiving drum as it first receives the ink from the ductor roll. The ductor roller is journaled in the top end of a pair of arms 7, which are fixed to a shaft 8, journaled in the side frames 1 of the machine. Fixed to the shaft 8 is an actuating arm 9, having a cam roller 10 running on a rotating cam 11. The cam is fixed on a shaft 12, which is journaled in the printing press frame 1. Suitable devices for regulating the position and action of the ductor roller 5 relatively to the fountain roller 3 and ink drum 6 are provided, and as shown, these devices 13 are interposed between the shaft 8 and the roller 10, and likewise may be of any known or suitable form. A suitable spring (not shown) is usually employed to yieldingly impel the ductor roller 5 to the fountain roller and to keep the roller 10 to its cam 11.

The ink drum 6 has a shaft 14 journaled in the side frames 1 of the press, and it is driven by suitable gearing or other means of any known or convenient form, and is preferably non-vibrating.

In accordance with one feature of the invention there are separate trains of ink preparing and conveying devices to the form cylinder, each of these trains having various

features and characteristics directed to efficient inking action, and to effect such action for either direction of rotation of the form cylinder.

- 5 As embodied, and referring primarily to the upper train of inking devices, an inking roller 25 cooperates with ink drum 6 and with an ink drum 26, which drum has its shaft 27 journaled in the machine frame.
- 10 The ink roller 25 is preferably provided with vibrating means, which are indicated at 24. The inking drum 26 is provided with any suitable rotating means, and also with any suitable vibrating means, the latter being 15 indicated generally by 28.

In turn an inking roller 29 coacts with the ink drum 26 and also with an ink drum 30, the shaft 31 of which is journaled in the press frames 1. Inking roller 29 is preferably non-vibrating. The ink drum 30 is likewise rotated by any suitable gearing and is provided with any suitable vibrating means 32. Cooperating with the ink drum 30 and with the form cylinder 35 are a pair 25 of form inking rollers 36 and 37.

Referring now to the other train of inking devices between the ink fountain and form cylinder, an inking roller 43 coacts with ink drum 6 and with an inking drum 44, the shaft 45 of which is journaled in the side frames 1 of the press. Ink roller 43 is preferably provided with vibrating means, indicated generally at 42. Ink drum 44 is rotated by any suitable gearing and is provided with any convenient form of longitudinal vibrating means 46.

Coacting with ink drum 44 and also with an ink drum 47 is an ink roller 48. This ink roller is preferably stationary. Ink drum 47 has its shaft 49 journaled in the side frames 1 of the press, and is rotated by any suitable gearing, and is provided with any suitable longitudinal vibrating means 50. Two form inking rollers 51 and 52 cooperate 45 with the inking drum 47 and with the form cylinder 35. An impression cylinder 53 constitutes a printing couple with the form cylinder 35.

Referring now more especially to Figs. 1 and 6 to explain certain general features of the invention, the various ink conveying members are of different diameters and are vibrating and non-vibrating in certain relations so as to effect a thorough and absolutely even distribution of the ink without any lines or streaks or shade marks.

As embodied, the inking drum 6 is of relatively large diameter, and is rotatably driven, but is preferably non-vibrating. The ink drum 26 is preferably considerably smaller in diameter and circumference than the ink drum 6, and is rotatably driven and preferably vibrated. The ink drum 30 is in turn preferably of less diameter and circumference than the ink drum 26, and is rotatably

driven and preferably vibrated. The relative proportion of the drum 30 to the drum 26 may be considerably different from that of the drum 26 to the drum 6.

The vibrating ink roller 25 is located above 70 the line of centers of its coacting inking drums and this is true to even a larger degree with respect to the stationary inking roller 29. The form inking roller 36 is of greater diameter and circumference than the 75 other form inking roller 37, which also cooperates with the ink drum 30. Thus the inking rollers will not sag, and placing and displacing is rendered both easy and simple. There is also positive assurance that the 80 roller is riding in the sockets, thereby obviating wear on the composition.

The larger form roller 36 imparts the first inking to the plates on form cylinder 85 35 when it is rotating in the clock-wise direction. This insures uniform inking and an equal amount of inking whether the press is running in one direction or the other.

It will be understood that the actual proportions, and also the relative proportions 90 of these various drums and rollers may be varied within the scope of the invention. It is, however, important that their various circumferences be different, as this insures different parts on two directly coacting 95 drums and rollers coming into ink-conveying contact on the successive revolutions of the drums or cylinders.

That is, on successive revolutions, and employing for convenience geometrical terminology, on each successive revolution of an ink drum and ink roller, two different elements of the two cylinders come into ink conveying contact and so on indefinitely. Also the ink rollers with their variable bearings are mounted above one or both of the ink drums which coact therewith, and thus are capacitated to rest thereon positively and firmly. Also the larger form inking roller of each group cooperates first with the form 110 cylinder, when this pair of form inking rollers are in the lead with respect to the direction of rotation of the form cylinder. While two inking form rollers have been referred to, it will be obvious that a larger 115 number may be used.

Referring now to the other separate train of inking rollers and ink drums operating between the inking fountain and the impression cylinder this has preferably the same 120 general novel features as that already described. As embodied, ink drum 44 is of less diameter and circumference than ink drum 6, and ink drum 47 is of greater diameter and circumference than ink drum 44, but less than ink drum 6. The vibrating ink roll 43 rests upon and above ink drum 44, and non-vibrating ink roll 48 is likewise above or in contact with the upper parts of the two ink drums 44 and 47.

A form inking roller 52 is likewise preferably larger than the other form inking roller 51 for this same group of mechanism, and cooperates first with the form cylinder 35 when it is rotating in the counter clockwise direction.

The same general statements as to proportions, general position and the like which have been made in connection with the 10 upper train of rollers and drums applies also to this series, including the explanation that on successive rotations a new part or element of each drum and cylinder comes in contact with the coacting roller or drum and 15 so on indefinitely.

Referring now in detail to the positioning means for the ink rollers, both stationary and vibrating, shown in Figs. 4 and 5 of the drawings, the various shafts 60 thereof 20 have a bearing 61 at either side, formed at the end of a corresponding bar or plate 62. The bar or plate 62 is provided with an elongated slot 63, through which projects a clamping screw bolt 64, which is screw-threaded into the press frame 1. Contacting with the end of the plate or bar 62 is the turning head 65 of a screw 66, which is screw-threaded into a tapped lug 64 formed on the press frame 1.

30 On its right-hand side, bar or plate 62 is in engagement with the turning head 70 of a screw 71, which is screw-threaded into a tapped lug 72 formed on the press frame. On its left-hand side, the bar or plate 62 is in engagement with the turning head 74 of a screw 75 which is screwed into a tapped lug 76 formed on the press frame 1. Thus the position of the inking roller may be regulated so that it may be made to press 40 more heavily or more lightly against the inking drum at either side, or may be made to press either more lightly or heavily against both of the inking drums without changing its relative coaction with either.

45 Referring now to the position regulating means for the form inking rollers (Figs. 2 and 3), the shaft 80 of each form inking roller is journaled in a bearing 81, at either end thereof, the bearings 81 being carried at 50 the ends of corresponding bars or plates 82 at either side of the press. Each bar or plate 82 is nested in, and is longitudinally reciprocable in, a correspondingly-shaped guideway in a plate 85. Each bar or plate 55 82 has an elongated slot 83 therein a clamping screw bolt 84 projecting therethrough and being screw-threaded into the plate 85.

For the purpose of longitudinally positioning the plate or bar 82 relatively to its 60 supporting plate 85, a screw rod 89 is screw-threaded into the plate 82, and is rotatably journaled in a lug 90 formed on an extension 91 of the plate 85. A collar 92 on one side of the lug 90, and the turning head 65 65 on the other side thereof, holds the screw

rod 89 longitudinally in position, and by turning it, the plate 82 may be slid to and fro along its guideway and be held accurately in any desired position.

The embodied form of means for positioning the form-inking roller relatively to its inking drum, comprises an elongated and preferably arcuate slot 97 formed in the plate 85, a screw-bolt 98 projecting therethrough and being screw-threaded in a base 99, which base is fixed to the press frame 1 in any suitable manner as by machine screws 100. Abutting against the right-hand side or edge of the plate 85 in Fig. 2 is the turning head 104 of a screw 105, 80 which is screw-threaded into a lug 106 formed on the press frame 1. A turning head 107 of a screw 108 abuts against the left-hand side of the plate 85 in Fig. 2, the screw-rod being screw-threaded into a lug 109, 85 formed on the machine frame. Thus there is likewise either simultaneous or independent relative position of the form inking rollers relatively to the form cylinder or to the coacting inking drum, the positioning transversely being substantially on a radius from the center of the form cylinder.

The invention in its broader aspects is not limited to the specific mechanisms shown and described but departures may be made 95 therefrom within the scope of the accompanying claims without departing from the principles of the invention and without sacrificing its chief advantages.

What I claim is:—

1. A printing press including, in combination, printing devices including a form cylinder, an inking mechanism therefor comprising a plurality of ink drums, a plurality of inking rollers of different sizes comprising vibrating and non-vibrating rollers cooperating therewith and rotating in the same direction at their contiguous surfaces and at the same surface speed, a plurality of form inking rollers, means for moving 100 said form inking rollers rectilinearly, and means for moving said form inking rollers circumferentially about said form cylinder.

2. A printing press including, in combination, printing devices including a form cylinder, an inking mechanism therefor comprising a plurality of ink drums, a plurality of inking rollers of different sizes comprising vibrating and non-vibrating rollers 115 cooperating therewith and rotating in the same direction at their contiguous surfaces and at the same surface speed, a plurality of similar pairs of form inking rollers of different sizes arranged symmetrically about said form cylinder, means for moving said form inking rollers rectilinearly, and means for moving said form inking rollers circumferentially about said form cylinder.

3. A printing press including, in combination, printing devices including a form cyl- 130

- inder, an inking mechanism therefor comprising a plurality of ink drums, a plurality of inking rollers of different sizes comprising vibrating and non-vibrating rollers co-
operating therewith and rotating in the same direction at their contiguous surfaces and at the same surface speed, means for moving said rollers rectilinearly with respect to their cooperating ink drums, a plurality of similar pairs of form inking rollers of different sizes arranged symmetrically about said form cylinder, means for moving said form inking rollers rectilinearly, and means for moving said form inking rollers circumferentially about said form cylinder.
4. A printing press including, in combination, printing devices including a form cylinder, an inking mechanism therefor comprising a plurality of series of ink drums of different sizes, a plurality of inking rollers of different sizes, cooperating with the ink drums of each series, located above the line of centers of adjacent drums and rotating at the same surface speed as said drums and in the same direction at their contiguous surfaces, means for moving said rollers rectilinearly with respect to their cooperating ink drums, a plurality of similar pairs of form inking rollers of different sizes arranged symmetrically about said form cylinder, means for moving said form inking rollers rectilinearly, and means for moving said form inking rollers circumferentially about said form cylinder.
5. A printing press including in combination rotary printing devices and inking mechanism therefor including an ink fountain and a plurality of separate trains of ink distributing and forwarding members between the ink fountain and the printing devices including ink drums and mutually interposed inking rollers, the inking rollers in each train being above the line of centers of their respective contiguous ink drums.
6. A printing press including in combination rotary printing devices and inking mechanism therefor including an ink fountain and a plurality of separate trains of ink distributing and forwarding members between the ink fountain and the printing devices including ink drums and mutually interposed inking rollers, the inking rollers in each train being above the line of centers of and supported by their respective contiguous ink drums.
7. A printing press including in combination rotary printing devices and inking mechanism therefor including an ink fountain and a plurality of separate trains of ink distributing and forwarding members between the ink fountain and the printing de-

vices including ink drums of varying diameters and mutually interposed inking rollers, the inking rollers in each train being above the line of centers of their respective contiguous ink drums.

8. A printing press including in combination rotary printing devices and inking mechanism therefor including an ink fountain and a plurality of trains of ink distributing devices each train including a common non-vibrating and a plurality of vibrating ink drums and mutually interposed inking rollers, the inking rollers in each train being above the line of centers of their respective contiguous ink drums.

9. A printing press including in combination rotary printing devices and inking mechanism therefor including an ink fountain and a plurality of trains of ink distributing and forwarding members between the ink fountain and the printing devices each train including a common non-vibrating and a plurality of vibrating ink drums and mutually interposed inking rollers, the inking rollers in each train being above the line of centers of and supported by their respective contiguous ink drums.

10. A printing press including in combination rotary printing devices and inking mechanism therefor including an ink fountain and a plurality of trains of ink distributing devices each train including a common non-vibrating and a plurality of vibrating ink drums and mutually interposed inking rollers, the inking rollers in each train being above the line of centers of their respective contiguous ink drums, the inking rollers contiguous to the non-vibrating ink drum and a vibrating ink drum being vibrating and those contiguous to vibrating ink drums being non-vibrating.

11. A printing press including a combination rotary printing devices and inking mechanism therefor including an ink fountain and a plurality of trains of ink distributing and forwarding members between the ink fountain and the printing devices each train including a common non-vibrating and a plurality of vibrating ink drums and mutually interposed inking rollers, the inking rollers in each train being above the line of centers of and supported by their respective contiguous ink drums, the inking rollers contiguous to the non-vibrating ink drum and a vibrating ink drum being vibrating and those contiguous to vibrating ink drums being non-vibrating.

In testimony whereof, I have signed my name to this specification.

MARTIN W. BRUESHABER.
